Primary Examiner — Catherine Tuttle(74) *Attorney, Agent, or Firm* — Womble Carlyle Sandridge & Rice, LLP**CLAIM**

The ornamental design for a spray dispensing container, as shown and described.

DESCRIPTION

FIG. 1 is a top, front perspective view of a spray dispensing container showing our new design in a closed configuration, the front end of the container including a transparent surface; FIG. 2 is a bottom, rear perspective view of the spray dispensing container illustrated in FIG. 1;

FIG. 3 is a side view thereof;

FIG. 4 is a side view thereof, wherein the container is rotated along a horizontal axis 180° in relation to the view illustrated in FIG. 3;

FIG. 5 is a rear view thereof;

FIG. 6 is a front view thereof;

FIG. 7 is a top plan view thereof;

FIG. 8 is a bottom plan view thereof; and,

FIG. 9 is a top, front perspective view showing our new design in an open configuration.
